United States Patent Office

Des. 213,266
Patented Jan. 28, 1969

213,266

STORAGE CABINET OR SIMILAR ARTICLE

Donald R. Kracke, 5620 White Cliff Drive,
Palos Verdes Peninsula, Calif. 90274

Filed July 28, 1967, Ser. No. 8,040

Term of patent 14 years

U.S. Cl. D33—19

Int. Cl. D6—01

Fig. 1

Fig. 2

The back of the cabinet is a plain flat wall.

The dominant features of my design reside in those portions shown in full lines on the drawing.

I claim:

The ornamental design for storage cabinet or similar article, as shown and described.
